UNITED STATES PATENT OFFICE.

WALTER CHAUNCEY CAMP, OF NEW HAVEN, CONNECTICUT, ASSIGNOR
OF ONE-HALF TO CHARLES CROSS GOODRICH, OF AKRON, OHIO.

DEVICE FOR USE IN PLAYING THE GAME OF GOLF.

No. 802,628.

Specification of Letters Patent.

Patented Oct. 24, 1905.

Application filed May 6, 1905. Serial No. 259,154.

To all whom it may concern:

Be it known that I, WALTER CHAUNCEY CAMP, a citizen of the United States, residing at New Haven, in the county of New Haven and State of Connecticut, have invented a new and useful Improvement in Devices for Use in Playing the Game of Golf, of which the following is a specification.

Many golf-players in swinging a golf-club in the act of striking the ball develop a tendency to bend the arms at or about the moment the ball is struck, thus preventing the club-head from traveling in the exact direction of the line of flight in which the ball is to be projected, rendering the direction uncertain, and making it impossible for the player to attain the accuracy and precision of stroke and smooth "follow-through" which are necessary to successful play. The faults resulting from bending the arms in the manner described may become manifest in a number of ways—as, for example, in the common fault of drawing the club-head across the surface of the ball at the moment of impact, thus imparting a side twist or "slice" and deflecting the ball from the direction in which it is intended to go and also causing a loss of distance by reason of the curved line of flight, or in the fault of "topping" the ball, due to the drawing up of the arms and consequent lifting of the club-head. It is to correct and prevent these faults and others which arise from improper bending of the elbow-joint that my invention is designed.

My invention relates to a device to be worn upon the arm while playing the game of golf, it being intended to be worn upon the left arm of a right-handed and upon the right arm of a left-handed player.

To accomplish the desired result, I construct an elbow-wrapper of stiff material or material stiffened in any desired manner to prevent the player from bending the elbow to any great extent, and having means for fastening the said wrapper about the arm of the player, and preferably having a pad or guard constructed to receive the point of the elbow-joint, the pad serving the double purpose of assisting in maintaining the device securely in position and preventing injury or discomfort to the elbow of the player. I preferably construct the means of attachment to the arm in the form of buckles and straps, which may readily be adjusted at any

required tension, thus enabling the player to maintain the arm in a more or less bent position, if desired.

In the accompanying drawings, in which I have illustrated the best form of the invention now known to me, Figure 1 represents the device attached to an arm. Fig. 2 is a plan view of the device, and Fig. 3 is a cross-sectional view of a form of elbow cup or pad.

Like characters signify like parts in the drawings.

A is the elbow-wrapper, which I preferably construct of double layers of canvas, leather, or other material.

B B are stiffening-strips inserted between the layers and held in place in any suitable manner.

S S S S are straps of any suitable material for fastening the device to the arm.

w is a wire inserted between the layers of material in the main portion M to give the device the requisite stiffness, and it protrudes between the points 1 and 2 to form a means for attaching the elbow pad or cup. I preferably construct the elbow pad or cup of rubber and having an annular pneumatic ring r with an annular air-space x and fastened to or made integral with base c, which extends beyond the outer periphery of the ring r in the form of a flange f, the flange being adapted to be inserted under the protruding wires between the points 1 and 2. With this construction the cup or pad is held securely in place and may be readily removed for purposes of repair or renewal.

I preferably make the main portion M slightly curved lengthwise of the arm, as shown in Fig. 1, in order that it may more readily be adapted to the shape of the arm.

The materials and the details of construction may be different from those specified above without departing from my invention, and

What I claim as new, and desire to secure as my invention, is the following:

1. A device adapted for use in playing the game of golf consisting of a stiff support adapted to extend lengthwise of the arm from above to below the elbow, a pad for the elbow carried by said support and means for fastening such device to the arm.

2. A device adapted for use in playing the game of golf consisting of an arm-wrapper having a stiff portion adapted to extend lengthwise of the arm, means for fastening the said

portion to the arm at points above and below the elbow, and means carried by said portion for supporting the elbow.

3. A device adapted for use in playing the game of golf consisting of an arm-wrapper having a stiff portion adapted to extend lengthwise of the arm, a pad or cup carried thereby and adapted to receive the point of the elbow-joint, and means for securing the device to the arm of the wearer.

4. A device adapted for use in playing the game of golf, consisting of a stiff strip adapted to extend lengthwise of the arm, means carried thereby for supporting the elbow, and means for securing the device to the arm of the wearer.

5. An arm wrapper or stiffener adapted to be used in playing the game of golf, comprising a central stiff portion provided with a wire extending about and secured to the same, a cup or pad mounted upon the stiff portion adjacent to the center thereof, stiffening members secured adjacent to the outer edges of the wrapper, and means for fastening the wrapper to the arm of the wearer.

6. A device adapted for use in playing the game of golf, having a centrally-disposed, relatively stiff portion, a cup or pad carried by said portion, stiffeners located adjacent to the outer edges of the device, and means for fastening the device to the arm of the wearer.

7. A device adapted for use in playing the game of golf, provided with a centrally-disposed stiff portion, a cup or pad mounted upon said stiff portion at a point substantially central thereof, and means for securing the device to the arm of the wearer.

8. A device adapted for use in playing the game of golf having the stiff portion M, a yielding pad carried by said stiff portion, and means for securing the device to the arm of the wearer.

In testimony whereof I have signed my name to this specification, this 28th day of April, 1905, in the presence of two subscribing witnesses.

WALTER CHAUNCEY CAMP.
